UNITED STATES PATENT OFFICE.

ANTHONY F. MERONEK, OF POLONIA, WISCONSIN.

MANUALLY-OPERATED MECHANISM FOR OPERATING AND SECURING SWINGING DOORS.

Application filed June 5, 1924. Serial No. 718,124.

To all whom it may concern:

Be it known that I, ANTHONY F. MERONEK, a citizen of the United States, residing at Polonia, in the county of Portage and State of Wisconsin, have invented certain new and useful Improvements in Manually-Operated Mechanisms for Operating and Securing Swinging Doors; and I do declare the following to be a full, clear, and 10 exact description of the invention, such as will enable others skilled in the art to which it appertains to make and use the same.

This invention relates to an improved manually operated means for opening and closing swinging doors and releasably securing these doors in either an open or a closed position, the device being so constructed that a portion of the mechanism may constitute a handle by means of which 15 the doors may be opened and closed and a portion of the device constituting a latch for releasably securing the doors in either the open or the closed position.

Another object of the invention is to so 20 construct this structure that a pair of swinging doors may be simultaneously moved to either an open or a closed position when the handle portion of the device carried by one of the doors is grasped and turned to 25 release the latch and the door carrying the handle moved to either the open or the closed position.

Another object of the invention is to provide a device which may be operated from 30 either within or outside the garage.

Another object of the invention is to provide a structure of the character described which will be simple in construction and 35 easy to operate and not liable to readily get out of order.

This invention is illustrated in the accompanying drawings, wherein:

Figure 1 is a view showing the garage and door operating mechanism in top plan 40 with the garage shown in section and the doors shown closed.

Figure 2 is a view similar to Fig. 1 showing the doors open.

Figure 3 is a vertical sectional view 45 through the garage with the door-operating mechanism shown in side elevation and the doors secured in the closed position.

Figure 4 is a view similar to Fig. 3 showing the handle elements turned to move the

latches to the releasing position and permit 55 opening of the doors.

Figure 5 is a bottom plan view showing the latch in position to secure the doors when open.

This garage is indicated in general by 60 the letter G and will be provided with doors D hingedly mounted so that they may be swung outwardly from the closed position of Fig. 1 to the open position of Fig. 2. This is a conventional construction of garage and it will be understood that the garage and doors may be formed of any suitable material.

A bar 1 which may be termed a track bar or track element extends longitudinally 70 in the garage and has its end portions secured to the front and rear walls thereof above the level of the doors. It will thus be seen that this bar will be positioned at a sufficient height so that it will not interfere with an automobile entering or leaving the garage. This track bar 1 has been provided with lugs 2 and 3 as shown in Figs. 3 and 4 for engagement by the catch arms 4^a and 4^b of the latch 4 which is pivotally 75 carried by a carriage 5 positioned beneath the track bar and provided with side flanges 6 which overlap the side portions of the track bar and thus slidably mount the carriage. The latch is pivotally mounted by 80 means of a pin 7, and is provided intermediate its length with a crank arm 8 by means of which it may be moved to an inoperative position. It will be readily seen that when the latch is rocked in one direction, the arms 4^a and 4^b will be swung against the action of the spring 9 which is positioned about the pin 7 and has its ends engaging the arms of the latch.

The handles 12 and 13 are rotatably 95 mounted by means of a bolt 14 which extends through one of the doors and it will thus be seen that when either of the handles is grasped and turned, the other handle will turn with it. The handle 12 is provided with an extension 15 having an opening formed therein so that a lock 16 may be passed through the opening of the extension 15 and through a similar opening formed in a bracket 17 to lock the handles against turning and thus prevent un-authorized opening of the doors. A plunger latch 18 is slidably mounted in a bracket 100

19 secured against the inner face of the handle-carrying door and yieldably held in position to engage the keeper 20 by means of the usual spring 21. This plunger-latch 18 is connected with the handle 13 by means of a wire, light chain or any other similar element 22 which will serve to cause the plunger to be drawn upwardly to the released position of Fig. 4 when the handles 10 are turned as shown in this figure. A bell-crank lever 23 is pivotally mounted by means of an ear 24 which extends downwardly from a draw-bar 25, the outer end of which is connected with the handle-carrying door by means of a bracket 26. A similar draw-bar 27 is pivotally connected with the other door by means of a bracket 28 and these two draw-bars have their inner ends loosely connected with the carriage by means 15 of the pivot pin 7. An abutment ear 29 extends from the bar 25 to engage the latch arm 4^b and limit pivotal movement thereof by the spring 9. The bell-crank lever 23 extends in a vertical plane and has its upper 20 arm connected with the crank arm 8 of the latch 4 by means of a wire, light chain or other similar connection 30 and has its horizontally disposed arm connected with the handle 13 at the opposite side thereof 25 from the flexible connection 22 by means of a similar connection 31. Therefore, when the handle is turned to the position shown in Fig. 4, the latch 4 will be swung to move the latch arm 4^b out of engagement with the lug 3 or the arm 4^a out of engagement 30 with the lug 2 according to whether doors are open or closed.

When this structure is applied to a garage, the track bar will extend longitudinally in 40 the garage and the bars 25 and 27 connected with the doors. The handles will be put in place and the handle 13 connected with the bell-crank lever 23 by means of the flexible connection 31 and then connected with the plunger-latch of the garage door by means of the chain or other similar connection 22. The doors can then be closed and when in this position, the latch arm 4^b will engage the lug 3 and secure 45 the doors in the closed position. If the operator is standing outside the garage, the padlock 16 can then be put in place and the handles cannot be turned to release the doors until the padlock is removed. When 50 the padlock is removed, the handle 12 can be turned and as this handle is turned, the handle 13 will turn with it thus drawing upon the flexible connections 22 and 31 to move the latch 18 to a releasing position and turn the bell-crank lever 23 to draw upon the flexible connection 30 and thus 55 rock the latch 4 upon the pin 7 to move the latch arm 4^b to a releasing position. With 60 the latch in the releasing position, the han-

dles can be pulled upon and as the handle-carrying door is drawn outwardly, the bars 25 and 27 will cause the carriage 5 to be moved longitudinally upon the track-bar towards the doorway and at the same time, cause the second door to be swung outwardly to the open position. When the doors begin to open, the handles 12 and 13 may be permitted to return to the position shown in Figs. 1 and 2 and the latch 4 will then be returned to the operative position 70 so that when the doors have been opened the full extent, the latch arm 4^a may engage the lug 2 and the doors be securely held in the open position and prevented from blowing shut when not desired. 75

There has thus been provided manually operated means for opening and closing the doors of the garage and for releasably securing the doors in either the open or the closed positions. There has further been provided means in which the latches may be moved to a releasing position by means of handles which will serve as ordinary handles for one of the doors. 80

I claim:

1. A mechanism of the character described comprising a suitably mounted track bar, lugs projecting therefrom, a carriage slidably mounted on said track bar, a latch pivotally mounted on said carriage, said latch comprising oppositely extending catch arms and a laterally projecting crank arm, draw-bars pivotally connected at their inner ends with said carriage and at their outer ends with a pair of doors, operatively connected handles disposed on opposite sides of one of said doors, and a latch releasing mechanism connected with one of said handles and with the crank arm of said latch, whereby the turning of said handle will actuate 106 the latch for disengaging the catch arms thereof from the lugs on said track bar. 95

2. A mechanism of the character described comprising a suitably mounted track bar, lugs projecting therefrom, a carriage slidably mounted on said track bar, a latch pivotally mounted on said carriage, said latch comprising oppositely extending catch arms and a laterally projecting crank arm, draw-bars pivotally connected at their inner ends with said carriage and at their outer ends with a pair of doors, operatively connected handles disposed on opposite sides of one of said doors, a latch releasing mechanism comprising a bell crank lever pivotally mounted on one of said draw-bars, a flexible connection between one arm of said lever and one of said handles, and a flexible connection between the other arm of said lever and the crank arm of said latch. 110

In testimony whereof I have hereunto set my hand.

ANTHONY F. MERONEK.
